UNITED STATES PATENT OFFICE.

ALBERT B. CHANCE, OF CENTRALIA, MISSOURI.

DESIGN FOR AN ANCHOR-ROD EYE.

56,273.

Specification for Design.

Patented Sept. 14, 1920.

Application filed December 29, 1919. Serial No. 348,186. Term of patent 14 years.

To all whom it may concern:

Be it known that I, ALBERT B. CHANCE, a citizen of the United States of America, residing at Centralia, in the county of Boone and State of Missouri, have invented a new, original, and ornamental Design for Anchor-Rod Eyes, of which the following is a specification, reference being had to the accompanying sheet of drawings, forming a part thereof and illustrating the invention.

Figure 1 of the drawings is a side elevation of my new design for anchor rod eyes; Fig. 2 is another side elevation of the same design, taken at right-angles to Fig. 1; and Fig. 3 is an end view of the anchor rod eye shown in Figs. 1 and 2.

The anchor rod eye of this invention consists of a formation substantially as shown,

comprising an eye for accommodating a guy strand or strain member, having a curved grooved portion extending outwardly from opposite sides of the eye portion for accommodating the guy strand or strain member and a thickened end portion for protecting or reinforcing the eye portion to prevent injury thereto in driving the anchor rod.

I claim:

The original design for an anchor rod eye substantially as shown and described.

As inventor of the foregoing I hereunto subscribe my name, this 24 day of December, 1919.

ALBERT B. CHANCE.
